UNITED STATES PATENT OFFICE.

JEFFREY T. FERRES, OF LOS ANGELES, CALIFORNIA.

MACHINE FOR MAKING CORRUGATED PAPER.

1,135,509.

Specification of Letters Patent. Patented Apr. 13, 1915.

Application filed November 19, 1912. Serial No. 732,287.

To all whom it may concern:

Be it known that I, JEFFREY T. FERRES, a citizen of the United States, residing at Los Angeles, in the county of Los Angeles, in the State of California, have invented certain new and useful Improvements in Machines for Making Corrugated Paper, of which the following is a specification.

My invention relates to a machine for making single faced corrugated paper board by corrugating a sheet of paper and attaching thereto by means of an adhesive a plain sheet of paper, and such invention pertains more particularly to the means for applying the adhesive in the operation of the machine.

One object of my invention is to provide means whereby the application of the adhesive is stopped and warning given the operator in case the paper should break or torn places or holes should occur therein, thereby assuring a perfect product.

Another object is to provide simple and efficient means for governing the amount of adhesive delivered to the tank or pan of the machine.

Still other objects are to provide means whereby the adhesive is applied to the paper in such manner that the amount thereof is always plainly visible to the operator, and also to provide means whereby the adhesive is prevented from coming into contact with and smearing the corrugating rolls.

Other novel and advantageous features of construction and operation will be apparent from the description hereinafter given.

In the drawings Figure 1 is a front elevation of my machine with portions thereof broken away; Fig. 2 a vertical sectional plan on the line 2—2 of Fig. 1; Fig. 3 a detail view of one of the gear wheels illustrating the manner of adjustment thereof upon its shaft, Fig. 4 a section on the line 4—4 of Fig. 3, and Fig. 5 a detail of a modified form of construction of plate or apron 27.

Referring to the particular embodiment of my invention as herein shown, the machine is provided with two similar end frames 1 which support the working parts of the machine and also the rolls of paper. In the present instance brackets 2 are bolted to the upper end of these frames as supports for the roll 3 supplying the sheet of paper to be corrugated. The end frames

have an extention 1^a at one of their lower corners to serve as a support for the roll 4 supplying the plain sheet of paper which is to be applied to the corrugated sheet.

The end frames are provided with vertical slots 5 within which are received and supported the bearing blocks 6 and 7 of the two corrugating rolls 8 and 9. These rolls are mounted in these slots and are adjustable as by means of the adjusting screws 10, in the usual and well known manner. As in ordinary practice these corrugating rolls which mesh with each other and consequently corrugate the sheet of paper passing between them and also are hollow and adapted to be heated by any suitable heating fluid such as steam in the ordinary way (not shown). Below the lowermost corrugating roll and also mounted within the slots 5 of the end frame is a plain roll 11 over which the plain sheet of paper passes just as it is being applied to the crowns of the corrugated sheet while still upon the lowermost corrugating roll.

By preference the plain roll 11 is grooved circumferentially at intervals along its length in order that there shall be less pressure at such intervals upon the facing strip and the crowns of the corrugated strip than at these portions of the plain roll of the full diameter where excess pressure might squeeze out all adhesive.

Shelves 12 formed integral with or separate from the end frames are provided for supporting the pan or tank 13 containing the adhesive which in practice is generally silicate. This pan is made so as to be readily removable for cleansing purposes the same being normally held in place upon the shelves by means of the dowel pins 14. The amount or level of adhesive in the pan is controlled automatically by the means clearly illustrated in Fig. 2.

As shown a flexible hose or tube 15 made of soft rubber leads from a source of supply of adhesive and extends into the pan or tank, the outlet end thereof being submerged in adhesive so that air cannot have access to the inside of the tube to cause hardening of the adhesive.

A bracket 16 is secured to one of the walls or sides of the pan and provided with an upwardly extending arm 16^a to which is fulcrumed a lever 17 of the first order.

To the inner end of this lever is pivoted a depending arm 18 carrying at its lower end a float 19 which floats upon the body of adhesive within the pan. To the other or outer end 5 of the lever is attached a depending arm 20 which is adapted to press upon and collapse the hose or tube 15 and thereby stop the supply of adhesive. It will be understood that this tube rests upon the bracket 16 so that 10 it may be collapsed as described when the arm 20 is moved downwardly by the rising of the float 19 when the level of adhesive in the pan has reached the predetermined point. When the level of the adhesive 15 lowers in the operation of the machine the arm 20 is raised and the adhesive permitted to flow through the tube into the pan, which flow is interrupted when the desired amount has been added to the pan. The supply of 20 the adhesive is consequently automatic.

A doctor roll 21 extends into the adhesive within the pan, such roll being suitably journaled at its ends in the end frames 1. Immediately above this doctor roll and 25 within the slots 22 in the end frame are mounted the bearing boxes 23 of the adhesive applying roll 24 which is adapted to receive the adhesive, for instance the adhesive, from the doctor roll, and in the present 30 instance to apply it to the plain sheet of paper which is to be attached to the corrugated sheet as hereinafter explained.

In order to apply the adhesive transversely of the plain sheet at such places only 35 where the crowns of the corrugated sheet come into contact therewith I provide this adhesive roll with the series of teeth 24^a. The adhesive roll is adapted to be adjusted vertically in suitable manner as by means 40 of the adjusting screws 25 which coöperate with the bearing boxes 23 thereof. The doctor roll is provided with an adjustable scraper 26 which is carried by a transverse bar 26^a supported at its ends in the main 45 frame 1.

Between the adhesive applying roll 24 and the plain roll 11 is interposed a plate or apron 27 which is horizontally grooved at 28 and pivoted toward its upper side at 50 29 to the end frames, such plate depending between said rolls. In Fig. 5 is shown a modified form of this plate or apron in which the plate 30 is provided at its top and bottom edges with the horizontal rollers 55 31 and 32 over which the paper passes. To the lower end of the plate or apron 27 at 33 is pivotally connected a rod 34 which in turn is connected by means of an adjusting device such as a turnbuckle 35 with a rod 36 60 which reciprocates through a bearing lug 37 projecting from one of the end frames. The outer end of this rod 36 constitutes the core of a solenoid indicated at 38, such core being normally held outward with respect to 65 the solenoid in suitable manner as by means

of the coiled spring 39 bearing at one end against the lug 36 and at the other end against the solenoid. When the parts are in the normal position thus shown in Fig. 2 the plate or apron 27 is in a position to bring the facing sheet of paper into contact with the teeth 24^a of the adhesive-applying roll, the proper adjustment being obtained by means of the turnbuckle described. The roll 24 is, in operation, in substantial contact with the doctor roll 21 and receives the adhesive therefrom upon the outer faces of its teeth. The sheet of paper does not pass between these two rolls but is presented by the plate or apron 27 to one side of the roll 24 which side may be termed the free side as distinguished from the part or side in contact with the doctor roll at any given time.

The solenoid 38 is in a suitable electrical circuit which, in the present instance, includes the wire 40, switch 41, wire 42, and a source of electric energy such as the battery 43 and a series of metallic pieces or fingers 44 which are loosely mounted upon a horizontal rod 45 whose ends are fastened in blocks 46 of insulating material. These fingers 44 are so suspended that they tend to drop by gravity toward the corrugating roll 9 and to contact the same in case no 30 paper is passing therethrough or in case any torn places or holes in the paper are presented. In case these fingers contact this roll the electric circuit is established through the wires described and through the roll 9 and thence to the frame of the machine and to the solenoid which is electrically connected with such frame. As a result the solenoid is energized and the armature rod 36 and associated parts attracted and drawn 35 thereby to the right (Fig. 2) instantly withdrawing the facing sheet from further contact with the adhesive applying roll. At the same time the electrical alarm bell 47 which is also interposed in the described 40 circuit is sounded and the alarm or warning thereby given to the operator of the condition. As is usual in machines of this character the metallic paper guides 48 are provided in grooves cut circumferentially 45 in the corrugating roll 8 the same acting to hold the corrugated paper within the corrugations of the lowermost roll 9.

Describing the driving connections which 50 may be of any desired character the power is applied to the pulley 49 secured to the shaft 50 of the corrugating roll 9. This shaft is provided with a gear 51 which meshes with the two gears 52 and 53, the former of which is secured to the shaft of 55 the corrugating roll 8 and the latter of which is secured to the shaft of the plain roll 11. The gear 53 meshes with an idler gear 54 secured to a horizontal shaft 55 mounted on the main frame, which latter 60

gear in turn meshes with and drives a gear 56 secured to the shaft 57 of the doctor roll 21. The driving connections thus far described are located at the right hand side 5 of the machine shown in Fig. 1. At the other end of the machine the plain roll is provided with a gear wheel 58 which is driven by a gear wheel 60 mounted on the extended shaft 61 of the doctor roll 21. As 10 shown in detail in Figs. 3 and 4 and for a purpose hereinafter explained, this gear wheel 60 is adjustable upon the shaft 61 to which end such gear wheel is provided with the two laterally extending lugs 62 arranged 15 at one side of its axis. Through these lugs pass the two adjusting screws 63 which co-operate with a lug 64 projecting from a collar 65 secured to the shaft 61. It will be understood that the gear wheel 60 is loosely 20 mounted upon the shaft 61 and the connection therewith is through the described lugs and adjusting screws. By adjusting these screws the relative position of the gear wheel with regard to the shaft 61 may be 25 adjusted.

Describing the operation of the machine and first following the course of the sheet to be corrugated, such sheet indicated at A 30 leads from the web or roll 3 over the idler rolls 66 and 67 and below the paper guides 48 and between the corrugating rolls 8 and 9 by which such paper is corrugated. The paper after passing between these rolls is carried around one side of the lowermost 35 roll 9 to a position in contact with the facing sheet B which is fed from the web or roll 4 over the idler rolls 68 and 69 and over the plate or apron 27. While passing over this plate the paper receives the adhesive from the toothed roll 24, the paste being thereupon applied in transverse strips which as hereinafter described, will match or register exactly with the crowns when reached in the further progress of this 40 facing sheet B. The facing sheet continuing bears upon the plain roll B and is applied with pressure to the crowns of the corrugated sheet still held within the lowermost 45 corrugating roll 9, these crowns contacting the facing sheet at the points or lines where the adhesive has been applied. The two sheets then emerge from the machine as completed single faced corrugated paper board. In case the corrugated sheet should 50 break or have a hole or torn place in it, the electrical devices described will be called into action, with the result that the apron 27 will be drawn to the right (Fig. 2) and likewise the facing strip will be withdrawn 55 from contact with the adhesive applying roll so that no adhesive will be applied under these conditions. This is a matter of 60 advantage in that during the consequent stoppage of the machine the facing sheet is 65 prevented from adhering to the adhesive applying

roll and thereby prevented from becoming torn or damaged when the machine is started again.

It will be noted that the distance from the point where the toothed paste-applying roll applies the adhesive to the facing sheet B and from the point where the fingers 44 are adapted to contact the corrugating roll 9, is the same to the contact point of the rolls 9 and 11, with the result that no adhesive can get onto the corrugating rolls in case the paper should break or is full of holes.

The object of providing the adjusting device for the sprocket wheel 56 as detailed 80 in Figs. 3 and 4 is to have the strips or lines of adhesive applied to the facing or lining sheet by the toothed roll 24 come opposite to or in register with the high parts or crowns of the corrugated sheet as they pass between the rolls 9 and 11. An exact registration is obtained by adjusting this sprocket wheel in one direction or the other upon the shaft 57.

It will be understood that the driving 90 connections described are such that the pitch circumference of the rolls 8 and 9 travels at the same speed and that the outside circumference of the rolls 11, 21 and 24 all travel at this same speed. Whether wide or narrow paper is run, no change is required to be made in the adhesive applying mechanism as is the case in other machines for making corrugated paper board. Moreover, the described construction avoids the 95 necessity of cutting circular grooves in the adhesive applying roll to accommodate the paper guides or wires as used on other machines which arrangement was wasteful of the adhesive which also hardened on the 100 wires and broke them. Furthermore, in my machine there is no shifting of a heavy adhesive pan required and the bearings of the rolls 21 and 24 are far removed from the 105 adhesive which in former machines got into 110 the bearings and cut them out.

I claim:

1. In a machine of the class described, the combination of means for corrugating a sheet of paper, mechanism for applying 115 strips of adhesive to a facing sheet including a longitudinally-toothed adhesive applying roll adapted to receive adhesive on the outer faces of its teeth, said teeth being so spaced that the adhesive strips may register with 120 the corrugations of the corrugated sheet, means for applying the facing sheet to the toothed roll to receive the strips of adhesive and means for applying the facing sheet to the corrugated sheet.

2. In a machine of the class described, the combination of corrugating rolls for corrugating a sheet of paper, mechanism for applying strips of adhesive to a facing strip including a doctor roll and a longitudinally- 130

- toothed adhesive applying roll adapted to substantially contact with the doctor roll to thereby receive adhesive on the outer faces of its teeth from such roll, said teeth being so spaced that the adhesive strips may register with the corrugations of the corrugated sheet, means for applying the facing strip to the toothed roll, and means for applying the facing sheet to the corrugated sheet.
3. In a machine of the class described, the combination of means for corrugating a sheet of paper, mechanism for applying strips of adhesive to a facing sheet including a longitudinally-toothed adhesive applying roll adapted to receive adhesive on the outer faces of its teeth, said teeth being so spaced that the adhesive strips may register with the corrugations of the corrugated sheet, an adjustable plate over whose surface the facing sheet passes and which presents such facing sheet to a free side of the adhesive applying roll to receive said strips of adhesive, and means for applying the facing sheet to the corrugated sheet.
4. In a machine of the class described, the combination of rolls for corrugating a sheet of paper, means for applying a facing sheet thereto, a toothed roll for applying to the facing sheet strips of adhesive, the teeth of such roll being so spaced that the adhesive strips may register with the corrugations of the corrugated sheet, and means for yieldingly presenting the facing strip to the toothed roll to receive said strips of adhesive.
5. In a machine of the class described, the combination of corrugating rolls for corrugating a sheet of paper, and means for applying to the facing sheet of paper strips of adhesive adapted to register with the crowns of the corrugations of the corrugated sheet, means whereby the time of so applying the strips may be changed and means for applying the facing sheet to the corrugated sheet.
6. In a machine of the class described, the combination of corrugating rolls for corrugating a sheet of paper, a toothed roll for applying to the facing sheet of paper strips of adhesive adapted to register with the crowns of the corrugations of the corrugated sheet, an apron over which the facing sheet passes and which has a groove opposite the toothed roll, means for supplying the adhesive to the toothed roll and means for applying the facing sheet to the corrugated sheet.
7. In a machine of the class described, the combination of corrugating rolls for corrugating a sheet of paper, a toothed roll for applying to the facing sheet of paper strips of adhesive adapted to register with the crowns of the corrugations of the corrugated sheet, a grooved apron which is adjacent the toothed roll and over which the facing sheet passes, an adhesive receptacle, a roll for supplying adhesive therefrom to the toothed roll and means for applying the facing sheet to the corrugated sheet.
8. In a machine of the class described, the combination of corrugating rolls for corrugating a sheet of paper, a toothed roll for applying to the facing sheet of paper strips of adhesive adapted to register with the crowns of the corrugations of the corrugated sheet, means for supplying the adhesive to the toothed roll, driving connections for said corrugating rolls and the toothed roll including means for timing the same whereby the strips of the adhesive will register accurately with the crowns of the corrugations of the corrugated sheet and means for applying the facing sheet to the corrugated sheet.
9. In a machine of the class described, the combination of corrugating rolls for corrugating a sheet of paper, a toothed roll for applying to the facing sheet of paper strips of adhesive adapted to register with the crowns of the corrugations of the corrugated sheet, means for supplying the adhesive to the toothed roll, and driving connections for said corrugating rolls and the toothed roll including a gear wheel 56, shaft 57 on which it is loosely mounted, a sleeve 61 secured to the shaft and having a lug 60, said wheel having lugs 58, and adjusting screws passing through the lugs 58 and cooperating with lug 60 and means for applying the facing sheet to the corrugated sheet.
10. In a machine of the class described, the combination of corrugating rolls for corrugating a sheet of paper, means for applying adhesive to the facing sheet of paper, means for withdrawing the facing sheet from the adhesive applying means and means for applying the facing sheet to the corrugated sheet.
11. In a machine of the class described, the combination of corrugating rolls for corrugating a sheet of paper, means for applying adhesive to the facing sheet of paper, means for automatically withdrawing the facing sheet from the adhesive applying means and means for applying the facing sheet to the corrugated sheet.
12. In a machine of the class described, the combination of corrugating rolls for corrugating a sheet of paper, means for applying adhesive to the facing sheet of paper, electrically controlled means for automatically withdrawing the facing sheet from the adhesive applying means and means for applying the facing sheet to the corrugated sheet.
13. In a machine of the class described, the combination of corrugating rolls for corrugating a sheet of paper, means for applying adhesive to the facing sheet of paper, a movable plate over which the facing sheet passes before being applied to the corrugated sheet and which presents the same to the adhesive applying means, means for

operating the plate and means for applying the facing sheet to the corrugated sheet.

14. In a machine of the class described, the combination of corrugating rolls for

5 corrugating a sheet of paper, means for applying adhesive to the facing sheet of paper, a movable plate over which the facing sheet passes and which presents the same to the adhesive applying means, an operating rod

10 connected with the plate for withdrawing the same, an electrical device for actuating the rod, a series of fingers arranged in the path of the paper and arranged in the circuit of said device, any one of said fingers

15 being adapted to close the circuit in case the sheet is torn or has a hole in it and means for applying the facing sheet to the corrugated sheet.

15. In a machine of the class described,

20 the combination of corrugating rolls for corrugating a sheet of paper, means for applying adhesive to the facing sheet of paper, a movable plate over which the facing sheet passes and which presents the same to the adhesive applying means, an operating rod

25 connected with the plate for withdrawing the same, an electrical device for actuating the rod, a series of fingers coöperating with one of the corrugating rolls and arranged in the circuit of said device, any one of said fingers being adapted to close the circuit in case the corrugated sheet is torn or has a hole in it and means for applying the facing sheet to the corrugated sheet.

30 16. In a machine of the class described, the combination of corrugating rolls for corrugating a sheet of paper, means for applying adhesive to the facing sheet of paper, a movable plate over which the facing sheet

35 passes and which presents the same to the adhesive applying means, an operating rod connected with the plate for withdrawing the same, an electrical device for actuating the rod, an idler roll over which the paper

40 passes to the corrugating rolls, a series of fingers coöperating with one of the rolls and arranged in the circuit of said electrical device, any one of said fingers being adapted to close the circuit in case the sheet is torn or has a hole in it and means for applying the facing sheet to the corrugated sheet.

45 17. In a machine of the class described, the combination of corrugating rolls for corrugating a sheet of paper, means for applying adhesive to the facing sheet of paper, a movable plate over which the facing sheet passes and which presents the same to the adhesive applying means,

50 an operating rod connected with the plate for withdrawing the same, an electrical device for actuating the rod, a series of fingers coöperating with one of the corrugating rolls and arranged in the circuit of said device, any one of said fingers

55 being adapted to close the circuit in case the

corrugated sheet is torn or has a hole in it, and an alarm device also interposed in said circuit and means for applying the facing sheet to the corrugated sheet.

18. In a machine of the class described, 70 the combination of corrugating rolls for corrugating a sheet of paper, means for applying adhesive to the facing sheet of paper,

75 a movable plate over which the facing sheet passes and which presents the same to the adhesive applying means, means for adjusting the degree of movement of the plate and means for applying the facing sheet to the corrugated sheet.

19. In a machine of the class described, 80 the combination of corrugating rolls for corrugating a sheet of paper, means for applying adhesive to the facing sheet of paper,

85 a movable plate over which the facing sheet passes and which presents the same to the adhesive applying means, an operating rod connected with the plate, means for adjusting the length of the rod to vary the degree of movement of the plate and means for applying the facing sheet to the corrugated 90 sheet.

20. In a machine of the class described, the combination of corrugating rolls for corrugating a sheet of paper, means for applying adhesive to the facing sheet of paper, 95 a movable plate over which the facing sheet passes and which presents the same to the adhesive applying means, an operating rod connected with the plate and constituting

100 the core of a solenoid, a solenoid, an electrical circuit for the solenoid, means dependent upon the presence of holes in the corrugated sheet for closing the circuit and means for applying the facing sheet to the corrugated sheet.

21. In a machine of the class described, 105 the combination of corrugating rolls for corrugating a sheet of paper, means for applying adhesive to the facing sheet of paper,

110 a movable plate over which the facing sheet passes before being applied to the corrugated sheet and which presents the same to the adhesive applying means, electrically operated means arranged in an electrical circuit for moving said plate including fingers

115 coöperating with one of the corrugating rolls and adapted to close said circuit, said fingers and the adhesive applying means being arranged substantially the same distance from the point where the two sheets 120 are brought together and means for applying the facing sheet to the corrugated sheet.

22. In a machine of the class described, 125 the combination of corrugating rolls for corrugating a sheet of paper, a plain roll co-

operating with one of the corrugating rolls, an adhesive applying roll arranged adjacent the plain roll, means interposed between the plain roll and the adhesive roll, over which means the facing paper passes and 130

by which it is presented to the adhesive roll, the facing paper and corrugated sheet passing between a corrugating roll and the plain roll and being attached to each other 5 thereat.

23. In a machine of the class described, the combination of corrugating rolls for corrugating a sheet of paper, a plain roll co-operating with one of the corrugating rolls, 10 an adhesive applying roll arranged adjacent the plain roll, a movable plate interposed between the plain roll and the adhesive roll, over which plate the facing paper passes and by which it is presented to the adhesive roll, means for operating the plate, the facing paper and corrugated sheet passing between a corrugating roll and the plain roll and being attached to each other thereat.

24. In a machine of the class described, 20 the combination of corrugating rolls for corrugating a sheet of paper, a plain roll co-operating with one of the corrugating rolls, an adhesive applying roll arranged adjacent the plain roll, a plate suspended between the plain roll and the adhesive roll, over which plate the facing paper passes and by which

it is presented to the adhesive roll, means connected with the lower end of the plate for operating it, the facing paper and corrugated sheet passing between a corrugating 30 roll and the plain roll and being attached to each other thereat.

25. In a machine of the class described, the combination of corrugating rolls for corrugating a sheet of paper, means for applying to a facing sheet of paper strips of adhesive adapted to register with the crowns of the corrugations of the corrugated sheet, and a plain roll co-operating with one of the corrugating rolls, the corrugated sheet and 35 facing sheet passing between the plain roll and the adjacent corrugated roll, said plain roll having a series of circumferential 40 grooves at intervals along its length to prevent such pressure along the entire width 45 of the sheets that might squeeze out the adhesive.
